Primary Examiner — Janice Hallmark*Assistant Examiner* — Harold E Blackwell, II(74) *Attorney, Agent, or Firm* — Taylor English Duma LLP(57) **CLAIM**

I claim the ornamental design for a conduit hanger adapter, as shown and described.

DESCRIPTION

FIG. 1 is an isometric view of my new design; FIG. 2 is a top view of the design of FIG. 1; FIG. 3 is a bottom view of the design of FIG. 1; FIG. 4 is a first side view of the design of FIG. 1; FIG. 5 is a second side view of the design of FIG. 1; FIG. 6 is a first end view of the design of FIG. 1; and, FIG. 7 is a second end view of the design of FIG. 1. The invention pertains to an ornamental design for a conduit hanger adapter. The solid lines represent the bounds of the claimed design, whereas those features shown in broken lines form no part of the claimed design.
